KNOT TIER

Arthur Shortland, Leicester, England, assignor to
 Mellor Bromley & Co. Limited, Leicester, England, a British company

Application June 23, 1952, Serial No. 295,043

Claims priority, application Great Britain
 June 25, 1951

16 Claims. (Cl. 289—3)

1

This invention relates to knot-tying devices, and has reference particularly to such devices of the class adapted to tie or fasten together, mechanically, either initially separate slender and flexible bodies, or the opposite ends of a single body of this character.

Of the bodies capable of being knotted by the device of this invention may be quoted, by way of example, textile yarns or threads and other like filaments, twine, thin cords, and so on. For the sake of convenience in the following further description, however, the simple term "yarns" will be used in a generic sense to cover any appropriate slender and flexible bodies.

Knot-tying devices of this invention are principally intended for use in tying or fastening together ends of yarns being dealt with in textile machinery such, for instance, as spinning or winding machines, knitting machines, weaving looms and the like.

For knotting together yarns being dealt with in textile machinery as aforesaid it has heretofore been customary to use a so-called weavers' knotter of the rotary bill type, i. e. a device incorporating, inter alia, a tying head including a rotary bill about which the knot is formed, and means for stripping the knot from the bill. Knotters of this type, however, suffer from the disadvantage that knots produced thereby tend to slip—especially when particularly springy, smooth and lively yarns such as mohair, cross-bred, worsteds and smooth synthetic yarns are tied together. In fact, it has previously been practically impossible to tie certain of these yarns together into a knot, mechanically, with a conventional knot-tying device.

The object of the present invention is to provide a knot-tying device adapted to function on what is believed to be a novel principle and in such a way as to tie together, in knots which will not slip, the most intractable of textile yarns or yarn ends.

The knot-tying device constituting this invention comprises, in combination, a body including spaced sides slotted to receive yarn ends to be tied together, a hooked instrument which is both reciprocable and turnable about its axis within the body for engaging the yarn ends and forming the same into a knot, severing means in the body for severing the knot, means for pulling the yarn ends at opposite sides of the said knot for tightening the latter, and a manually operable member for initiating conjoint actuation of the hooked in-

2

strument and the associated yarn severing and tightening means.

The new or improved knot-tying device may advantageously also include means for holding the yarn ends throughout a knot-tying operation. These means may be included in the aforementioned means for pulling the yarn ends to tighten a formed knot, as will be hereinafter described.

- 10 The new or improved knot-tying device is principally intended for use in forming knots of the character described in co-pending Application Serial No. 295,042 dated June 23, 1952. Broadly considered, such a knot, which serves to tie together at least two yarn ends, includes the steps of (a) making at least one loop of one or both of the said ends with the aid of a hooked instrument, (b) by means of this instrument drawing through the said loop either a further 15 single loop, or the first of a plurality of successively interengaged loops, of either or both of the yarn ends, and (c) so manipulating the said instrument as to engage either or both of the yarn ends and pull the same through the further 20 single loop, or the last of the plurality of the said interengaged loops, as the case may be.

The hooked instrument may conveniently be in the form of a knitting needle, crochet hook or the like adapted to inter-knit or similarly interlace the yarn ends incorporated in a knot.

Such an instrument may, for instance, and as shown in the accompanying drawings, consist of a conventional knitting needle of the latch type.

- In any event, the hooked instrument is provided with a shank suitably mounted in the body of the device and is adapted to be turned to any desired extent about its longitudinal axis suchwise as to twist a yarn or yarns engaged by the instrument and form a loop. The extent of this 35 turning movement may vary considerably according to the account of twist to be imparted to an engaged yarn or yarns. Thus, for instance, the instrument may be turned through half or a larger fraction of a complete revolution, through 40 one revolution, through a little more than one revolution or even through two or more complete revolutions.

Usually there will be two suitably spaced pairs of slots formed in the sides of the body, one 45 to receive one yarn end and the other similarly to receive another yarn end. Yarn ends placed in the slots extend laterally across the device, i. e. transversely with respect to the hooked instrument.

The new or improved knot-tying device will

usually be made in a form in which it can be grasped in and secured upon the operator's hand or attached to a belt or the like worn by the operator.

In order that the invention may be more clearly understood and readily carried into practical effect, one specific constructional form of the improved knot-tying device and the manner of operation of the same in the production of a knot will now be described with reference to the accompanying drawings, wherein,

Figure 1 is a plan view of the device,

Figure 2 is a vertical sectional view of the same taken on the line 11—11 of Figure 1,

Figure 3 illustrates an enlarged view of one of the sides of the device, and mechanism at that side as seen in the direction of the arrow A in Figure 1,

Figure 4 is an enlarged detail side view of a portion of the device showing, more particularly, the means whereby a tied knot is finally tightened,

Figure 5 is an end view of the device as seen in the direction of the arrow B in Figure 4;

Figures 6-13 are enlarged detail perspective views illustrating, in successive stages, the manner in which the device functions to tie together two yarn ends.

For the sake of clarity all of the figures are drawn more than full-scale.

Referring to Figures 1-5, it will be seen that body 100 of the device comprises two flat side plates 1 and 2 which are spaced apart parallel to each other and connected by comparatively thick front and rear cross members 3 and 4 respectively. The front member 3 is made deeper than the rear member 4 and so increases the rigidity of the structure. The side plates 1 and 2, moreover, are drilled at appropriate points with pairs of aligned holes adapted to receive the ends of transverse spindles 5, 6, 7, 8, 9 and 10 upon which working components of the device are mounted to turn as will be hereinafter described. The ends of the transverse spindles, which extend right through the holes are reduced in diameter and screw-threaded to receive securing nuts 11. In this way shoulders are produced on said spindles, adjoining their screw-threaded end portions, and the side plates 1 and 2 are clamped up tightly to these shoulders by means of the nuts 11, thereby further enhancing the rigidity of the structure.

In this constructional example, the hooked instrument is in the form of a knitting needle 12 having a hook 13 and an associated pivoted latch 14. The shank 15 of the knitting needle 12 is in the form of an elongated barrel of circular shape in cross-section which extends freely through a bearing hole 3a in the front cross member 3. In the rear cross member 4 is secured one end of a fixed guide pin P which extends forwardly, parallel to the side plates 1 and 2, and engages in a central bore 15a formed in the barrel-like needle shank 15. The shank is accordingly free both to be moved back and forth axially through, and to be turned about its axis within, the bearing hole 3a, being guided during such movements by the fixed guide pin P. To enable the knitting needle 12 to be both advanced and retracted longitudinally as well as turned about its longitudinal axis, the needle shank 15 is, as shown in Figures 2, 3 and 5, formed from end to end both with a series of equi-distantly spaced annular grooves 16 and intervening circular racklike teeth 17 arranged

to mesh with a co-operating pinion 18 disposed with its axis of rotation at right angles to the longitudinal axis of the shank, and a series of longitudinal grooves 19 and intervening straight

teeth 20 meshing with a pinion 21, disposed with its axis of rotation parallel to the said longitudinal axis. The teeth 17 and 20 intersect each other at right angles so that, in the result, the exterior surface of the shank 15 has the appearance of being formed all over with regularly disposed embossments. Turning movements of the pinions 18 and 21 to produce the foregoing conjoint movements of the knitting needle are effected from rotary cams 22 and 23 through the medium of intermediate connections presently to be described. These cams are adapted to turn together about the axis of the transverse spindle 5 for which purpose they are fixed to, or integral with, a sleeve 24 (Figure 1) mounted to turn freely about the said spindle. Fast with the sleeve 24 is a pinion 25 with which is arranged to mesh a toothed quadrant 26 formed on a thumb-operable actuating lever 27. As shown more clearly in Figures 2 and 5, this actuating lever is provided at opposite sides with co-axial bosses 28 and 29 mounted to turn freely about the fixed transverse spindle 8. The actuating lever 27, moreover, is controlled by a helically coiled torsion spring 30 which surrounds the boss 29 and has its opposite ends arranged in contact with the upper edge of the lever and the underside of a pin 31 fixed in the side plate 1. Accordingly, each time the portion 27a of the actuating lever 27 is depressed by the operator's thumb, the toothed quadrant 26 will be turned clockwise, as viewed in Figure 2, against the action of the spring 30, with the result that the pinion 25 and hence also the two cams 22 and 23 will be rotated anticlockwise—to the extent of one revolution in the specific example illustrated. Upon release of the actuating lever, the whole mechanism, including the cams 22 and 23, will automatically idle back to its starting position under the spring action.

The needle shank 15 is moved back and forth, in accordance with knotting requirements, by causing appropriate oscillation of the pinion 18. In this connection it will be noted, from a consideration of Figures 1 and 2, that integral with the pinion 18 there is a smaller pinion 31 which is arranged in mesh with a toothed portion 32a of a curved lever 32. The rear end of this lever is bossed at 33 and mounted to turn freely about the fixed transverse spindle 9. At a location in front of the latter the lever 32 is formed with a forwardly projecting nose 32b in which is formed an open-ended slot 34. In this slot is engaged one end of a pin 35 carried by a lever 36 which is bossed at 37 and mounted to turn about the fixed transverse spindle 7. The opposite end of the pin 35 is engaged in an appropriately profiled endless track 38 formed in the inner face of the rotary cam 22. As will be seen in Figure 1, the cam 22 is positioned closely adjacent to the side plate 1. Thus, each time this cam is rotated, the lever 36 will be turned up and down to rock the curved lever 32 and so oscillate the pinions 31 and 18 with the result aforesaid.

The necessary turning movements of the needle shank 15 about its axis, conjointly with reciprocation thereof, are effected by appropriate operation of the pinion 21 which is mounted for turning movement about a stub axle 39 screwed into the front cross member 3. As depicted in

Figures 3 and 5, this pinion, which meshes with the teeth 20, is also arranged in mesh with a small gear 40 mounted to turn upon a further stub axle 41 screwed into the front cross member 3. Mounted to turn together with the gear 40 is a concentric pinion 42 which, in turn, is arranged in mesh with a toothed arcuate portion 43a at the leading end of a relatively long pivoted lever 43. The arcuate portion 43a extends laterally from the lever 43 to enable it properly to mesh with the pinion 42 which is disposed in a plane at right angles to that of the said lever. At its opposite end the lever 43 is provided with a boss 44 mounted to turn about the fixed transverse spindle 9. In front of this spindle the lever 43 is formed with a protuberant nose 43b which is slotted at 45 (Figure 3) to receive one end of a pin 46 carried by the outer end of a lever 47 pivotally mounted on the transverse spindle 7. A portion 43c of the lever 43 is upwardly arched, as depicted in Figure 3, to avoid the spindle 7. The end of the pin 46 remote from the lever 43 projects through the associated lever 47 into an appropriately profiled endless track 48 formed in the opposed face of the rotary cam 23. This latter cam is located closely adjacent to the side plate 2. Here again, the construction and operation of the device is such that as the cam 23 revolves, the lever 47 will be moved up and down at the dictates of the track 48, thereby rocking the lever 43 and effecting oscillation of the pin 21 through the medium of the toothed arcuate portion 43a, the pinion 42 and the gear 40.

To receive the yarn ends to be engaged, and tied together, by the needle 12, the upper edges of the side plates 1 and 2 have formed therein pairs of slots or recesses 49 and 50 respectively. Yarn ends, such as Y and Y¹ (Figures 6-13) placed in these slots or recesses extend laterally across the device, parallel to each other. On the outer side of, and spaced from, the side plate 1 there is a relatively thin and small guard plate 51 (see Figures 1 and 2) the lower straight edge 51a of which is disposed just above the bottoms of the adjacent slots or recesses 49. The side edges 51b of the guard plate 51 are curved and upwardly convergent. The truncated portion of the side plate 1 located between the slots or recesses 49 is bent out of the plane of the outer face of the said plate and has the guard plate 51 attached thereto, e. g. by welding. Accordingly, whenever yarn ends Y and Y¹ are being placed in position across the device in readiness for tying, they are guided into the bottoms of the slots or recesses 49 in the side plate 1 by means of the curved edges 51b of the guard plate 51 and are thereupon directed beneath the straight edge 51a by means of which they are prevented from lifting and coming adrift from these slots or recesses.

On the outer side of the side plate 2 there is provided a pivoted device G comprising two pairs of spring-influenced gripping jaws 52, 53 between which extend the yarn ends Y and Y¹ placed in the slots or recesses 50 in the said side plate. The outer jaws 52 of the two pairs are constituted by parallel arms which are pivotally mounted at their lower ends upon a spindle 54 and are rigidly connected at their rear edges by a back plate 55. The lower portion of the plate 55 is extended and bent inwards at right angles to the jaws 52 so as to provide an inwardly directed lug 55a (see Figure 5) adapted to be acted upon by the means and for the purpose hereinafter to be described. The spindle 54 is secured at its op-

posite ends in a pair of ears 56 which are bent out from the material of the side plate 2. In this connection, the lug 55a extends through and works in the rectangular opening 57 (Figure 4) produced in the side plate 2 by reason of bending out therefrom the spaced ears 56. The jaws 52, the connecting back plate 55 and its extension 55a may conveniently be bent to shape from an initially flat sheet metal blank. The jaws 52 are also connected by a spindle 58, and slidably engaged with the two spindles 54 and 58 are the inner jaws 53 of the two pairs. The said inner jaws are pressed up against the inner sides of the companion outer jaws 52 by means of a compression spring 59 which, as illustrated in Figure 4, is arranged to surround the upper spindle 58 with its opposite ends in contact with the opposing faces of the inner jaws. As depicted more clearly in Figure 4, the upper end portions 52a and 53a of the inner and outer gripping jaws 52 and 53 of each pair are relatively splayed into V form to correspond with the shaping of the flared slots or recesses 50. Accordingly, yarn ends pulled down into the bottoms of these slots or recesses will be engaged between and firmly held by the gripping jaws.

For cutting the yarn ends Y and Y¹ at the appropriate stage in a knot-tying operation, there is provided, in this particular example, a cutter element 60 which is pivotally mounted at 61 on and adjacent to the inner face of the side plate 1. As shown more clearly in Figures 1 and 2, the element 60 is provided with two upstanding yarn-shearing blades 62 and 63 having sharpened leading edges adapted to co-operate with relevant edges of the adjacently disposed slots or recesses 49. The tail 60a of the cutter element 60 is cranked outwardly from the side plate 1 and is slotted at 60b to receive a pin P projecting laterally from the free end of one arm 63a of a two-armed actuating lever 63. This lever is fulcrumed at 64 (see Figure 2), and the end of its other arm 63b is formed with a rounded nose arranged in contact with the peripheral edge of the rotary cam 22. This edge is formed with a lobe 65 so disposed that each time the cam 22 is turned through a complete revolution, the lever 63 will be rocked as a consequence of which the arm 63a will be raised to impart an operative stroke to the cutter element 60.

The lever 63 is controlled by a tension spring 66 arranged as shown in Figure 2.

For finally tightening a knot, both of the yarn ends tied together by manipulation of the needle 12 are simultaneously pulled in a direction away from the side plate 2. This tightening of the formed knot is effected by swinging the gripper device G outwardly, to the extent indicated by chain lines in Figure 5, at the termination of the knot-producing cycle. Conveniently for this purpose there is provided a further two-armed lever 67 the two arms 67a and 67b of which are separated laterally by a boss 68 mounted to turn about the fixed transverse spindle 10 (see Figure 5). The operative end of the arm 67a is adapted for engagement with the underside of the aforementioned lug 55a, whilst the tail end of the other arm 67b is furnished with a laterally extending pin 69 arranged in the path of the toothed quadrant 26, all as shown in Figures 4 and 5. Thus, each time the portion 27a of the actuating lever 27 is fully depressed, the leading end of the quadrant 26, as the latter approaches the end of its stroke, will act on the pin 69 thereby depressing the arm 67b and raising the arm

57a with the result that the gripper device G will be positively swung outwards. The device G is influenced by a torsion spring 70 which is arranged to surround the spindle 54, with its opposite ends bearing against the side plate 2 and the device G respectively. Accordingly, this device is swung outwards against the action of the spring 70 and is returned to its original position by the said spring whenever the automatic lever 27 is released.

10 The upstanding portion of the side plate 2 located between the two flared slots or recesses 50 therein is depressed suchwise as to produce on the inner face of this plate a protuberance 71 adapted to facilitate the tightening of a knot. A formed knot from which the needle 12 has been finally disengaged is pulled by the outwardly swinging gripper device G onto the protuberance 71 which supports the knot whilst the yarn ends Y and Y¹ are being pulled by the grippers. As will be appreciated, the portions of the said ends immediately adjoining the knot extend over the rounded surface of the protuberance 71 and it is this which facilitates the tightening.

15 The manner in which the device just described functions to tie together the two yarn ends Y and Y¹ into a knot K will now be described with reference to Figures 6-13. First the two ends are placed transversely across the device and position in the pairs of slots or recesses 49 and 50. As a consequence, the said yarn ends become located beneath the edge 51a of the guard plate 51 and are also drawn into and firmly held by the pairs of gripping jaws 52 and 53. The actuating lever 27 is then depressed, so that the knitting needle 12 advances, by an appropriate turning movement of the pinion 48 and hence also of the shank 15 dictated by the shape of the track 38 in the cam 22, to engage and take into its hook 13 the yarn end Y as shown in Figure 6. Thereupon the needle turns about its longitudinal axis, in the direction of the arrow C to the extent of half a revolution, so as to produce a loop L closed by a partial twist T in the engaged yarn end Y (see Figure 7). This turning motion of the needle is effected by the rotary cam 23 through the medium of the hereinbefore described intermediate connections, including the pinion 21 meshing with the needle shank 15. At this stage, the needle 12, with its hook 13 inverted and its latch 14 open, is advanced right through the closed loop L in the direction of the arrow D to the extent that the hook is engaged over the other yarn end Y¹ as depicted in Figure 8. Next, the needle is retracted by the cam 22 in the direction of the arrow E (Figure 9) so as to draw a loop L' of the yarn end Y¹ through the closed loop L of the yarn end Y; this action closes the latch 14. With its hook 13 still inverted, the needle 12 is then advanced again, as illustrated in Figure 10, as a consequence of which the latch 14 is opened. At the same time the needle shank 15 is turned about its longitudinal axis by the cam 23 to the extent of half a revolution in the direction of the arrow F for the purpose of positioning the needle hook 13 for subsequent engagement with the portions y and y¹ of both of the yarn ends Y and Y¹ respectively. The needle 12 is again retracted, by means of the cam 22, so that it takes into its open hook 13 first the portion y¹ (Figure 11) and then the portion y and draws these portions right through the loop L'. In Figure 12, the portions y and y¹ of the yarn ends Y and Y¹ are shown in the course of being pulled through the loop L'. At this juncture, moreover, and also as shown in

10 Figure 12, the cutter element 60 is turned forwardly about its pivot 61 so that the shearing blades 62 and 63 function to cut the portions y and y¹ of the two yarn ends fairly close to the interengaged loops. During all of the foregoing stages the yarn ends Y and Y¹ are firmly held by the gripper device G. But after the portions y and y¹ of the yarn ends have been cut and pulled through the loop L', the gripper device G is swung outwardly as depicted in Figure 13 to tighten the completed knot K.

15 The entire sequence just described takes place as the result of a single movement of the actuating lever 27 against the action of the torsion spring 30. At the termination of this sequence, the actuating lever 27 is released and all of the co-operating components of the device are restored to their original positions by the spring 30.

20 As illustrated in Figure 4, there is secured to the side plates 1 and 2 a component 72 from which depends a portion 73 for association with a strap (not shown) enabling the device to be secured upon the operator's hand.

I claim:

25 1. A knot-tying device of the class herein referred to comprising, in combination, yarn ends, a body including spaced sides slotted to receive the yarn ends to be tied together, a hooked instrument which is both reciprocable and turnable about its longitudinal axis within the body for engaging the yarn ends and forming the same into a knot, severing means in the body for cutting the yarn ends close to the formed knot, means for pulling the yarn ends at opposite sides of the 30 said knot for tightening the latter, and a manually operable member for initiating conjoint actuation of the hooked instrument and the associated yard severing and knot tightening means.

35 2. A knot-tying device according to claim 1, which includes means for holding the yarn ends throughout a knot-tying operation.

40 3. A knot-tying device according to claim 1, wherein the hooked instrument consists of a knitting needle, e. g. of the latch type.

45 4. A knot-tying device according to claim 1, wherein the hooked instrument is provided with a shank which is formed for intermeshing engagement with toothed members whereby the instrument is moved back and forth longitudinally and turned about its axis.

50 5. A knot-tying device of the class herein referred to comprising, in combination, a body including spaced sides slotted to receive yarn ends to be tied together, a hooked instrument which is both reciprocable and turnable about its axis within the body for engaging the yarn ends and forming the same into a knot, the said hooked instrument having a cylindrical shank formed both with a series of spaced annular grooves and intervening circular teeth and also a series of longitudinal grooves and intervening straight teeth, a toothed member in the form of a pinion which has its axis disposed transversely with respect to the said shank and is arranged in mesh with the circular teeth, a further toothed member in the form of a pinion which is disposed with its axis parallel to the shank and arranged in mesh with the straight teeth, severing means in the body for cutting the yarn ends close to the formed knot, means for pulling the yarn ends at opposite sides of the said knot for tightening the latter, a manually operable member, and means actuated by the said member for rotating the aforesaid pinions and also for operating the

yarn severing means and the knot tightening means conjointly therewith.

6. A knot-tying device according to claim 5, wherein movements of the toothed members to produce the desired conjoint reciprocation and turning movements of the hooked instrument are effected from rotary cams adapted to be rotated by the manually operable member.

7. A knot-tying device according to claim 6, wherein there are two rotary cams, viz. one for controlling the movements of the pinion having its axis disposed transversely with respect to the shank of the hooked instrument, and the other for controlling the pinion disposed with its axis parallel to the said shank.

8. A knot-tying device of the class herein referred to comprising, in combination, a body including spaced sides slotted to receive yarn ends to be tied together, a hooked instrument which is both reciprocable and turnable about its axis within the body for engaging the yarn ends and forming the same into a knot, the said hooked instrument having a cylindrical shank formed both with a series of spaced annular grooves and intervening circular teeth and also a series of longitudinal grooves and intervening straight teeth, a toothed member in the form of a pinion which has its axis disposed transversely with respect to the said shank and is arranged in mesh with the circular teeth, a further toothed member in the form of a pinion which is disposed with its axis parallel to the shank and arranged in mesh with the straight teeth, rotary cams from which the movements of the pinions are controlled, a pinion turnable together with the said rotary cams, a manually operable member consisting of a pivoted lever, a toothed quadrant provided on the said member and arranged in mesh with the last mentioned pinion, severing means in the body for cutting the yarn ends close to the formed knot, means operable from one of the rotary cams for actuating the yarn severing means, means for pulling the yarn ends at opposite sides of the knot for tightening the latter, and means arranged to be operated by the manually operable member for actuating the knot-tightening means.

9. A knot-tying device according to claim 8, wherein each of the said two pinions has associated therewith a further pinion arranged in mesh with the toothed portion of a pivoted lever having a pin-and-slot connection with another pivoted lever adapted to be actuated by the relevant rotary cam.

10. A knot-tying device according to claim 8, wherein the manually operable member is influenced by a spring serving to return all of the co-operating components of the device to their original positions upon release of the said member at the termination of a knot-tying operation.

11. A knot-tying device according to claim 8, wherein the severing means consists of a movable cutter element provided with shearing blades arranged for co-operation with edges of the yarn-receiving slots in the appropriate side of the body of the device.

12. A knot-tying device of the class herein referred to comprising, in combination, a body including spaced sides slotted to receive yarn ends to be tied together, a hooked instrument which is both reciprocable and turnable about its axis within the body for engaging the yarn ends and forming the same into a knot, the said hooked instrument having a cylindrical shank formed both with a series of spaced annular

grooves and intervening circular teeth and also a series of longitudinal grooves and intervening straight teeth, a toothed member in the form of a pinion which has its axis disposed transversely with respect to the said shank and is arranged in mesh with the circular teeth, a further toothed member in the form of a pinion which is disposed with its axis parallel to the shank and arranged in mesh with the straight teeth, rotary cams from which the movements of the pinions are controlled, a pinion turnable together with the said rotary cams, a manually operable member consisting of a pivoted lever, a toothed quadrant provided on the said member and arranged in mesh with the last mentioned pinion, a movable cutter element provided with shearing blades arranged for co-operation with edges of the yarn-receiving slots in one side of the body of the device, a pivoted actuating lever which is connected to the said cutter element and is adapted in turn to be actuated by that rotary cam serving to control the pinion having its axis disposed transversely with respect to the shank of the hooked instrument, means for pulling the yarn ends at opposite sides of the knot for tightening the latter, and means arranged to be operated by the manually operable member for actuating the knot-tightening means.

13. A knot-tying device according to claim 12, wherein the cutter element is pivoted on the said side of the body.

14. A knot-tying device of the class herein referred to comprising, in combination, a body including spaced sides slotted to receive yarn ends to be tied together, a hooked instrument which is both reciprocable and turnable about its axis within the body for engaging the yarn ends and forming the same into a knot, severing means in the body of cutting the yarn ends close to the formed knot, means for pulling the yarn ends at opposite sides of the said knot for tightening the latter, means for holding the yarn ends throughout a knot-tying operation, the said means being combined with the means for pulling the said ends to tighten a formed knot, and a manually operable member for initiating conjoint actuation of the hooked instrument and the associated yarn severing and knot-tightening means.

15. A knot-tying device according to claim 14, wherein the said combined yarn holding and knot-tying means comprise pairs of spring-influenced grippers which are normally located adjacent to the yarn-receiving slots in the appropriate side of the body of the device to hold the yarn ends during a knot-tying operation, but are adapted to be moved away from the said side to pull the said ends and so tighten the knot at the termination of the operation.

16. A knot-tying device according to claim 15, wherein the yarn grippers are connected and pivotally mounted on the outside of the body, and a lever adapted to be actuated by the manually operable member is provided for swinging the grippers away from the body at the termination of a knot-tying operation.
